FIG. 6 is a bottom view thereof; and,

FIG. 7 is a front side view thereof, also showing an example positioning of an example knife stowed within my knife sheath.

A portion of the disclosure of this patent application contains material which is the subject of copyright protection. The copyright owner has no objection to the facsimile reproduction by anyone of the documents within this patent application or the patent disclosure as it appears in the United States Patent and Trademark Office patent file or records, but otherwise reserves all copyright rights whatsoever.

As illustrated in FIGS. 2-7, the knife sheath includes a strap across the back with generally horizontally-oriented top and bottom edges, each having a complex curved edge, and generally horizontally centered points. In some implementations, the knife sheath includes a pocket and strap for holding knife within the knife sheath, which knife includes ornamental features.

The "WK" trademark and logo incorporating the same in the drawings and forming a part of the disclosure are trademarks of Carpediem Group, LLC.

The broken lines illustrate environmental features that form no part of the claimed design. The surface shading and contour lines shown in the drawings represent the three-dimensional character and contour of the article, and are not intended to illustrate material, surface ornamentation or surface decoration.
